ABSTRACT OF THE DISCLOSURE

A deflection circuit that includes a unidirectional transistor having its collector connected to the deflection coil. Inductive coupling means are provided between the base and emitter for applying a switching signal thereto. The switching signal cuts off the transistor for a period that is longer than the flyback period whereby the deflection coil reverses polarity to forward bias the base-collector junction of the transistor which allows a reverse current to flow in the deflection coil via said base-collector junction to initiate the forward stroke of the deflection current. The amplitude of the transistor supply voltage is at least ten times the peak-to-peak amplitude of the switching signal.

The present invention relates to a deflection circuit for producing a sawtooth current in the line-deflection coils of a display tube. The deflection circuit is being provided with a transistor having an output circuit that includes the deflection coils. By means of an inductive coupling between the base and the emitter electrode, a pulsatory switching signal is applied to the transistor which cuts off and releases the transistor periodically.

Such a circuit arrangement is known inter alia from the U.S. Patent 3,143,686. However, the transistor used in this circuit arrangement is of the symmetrical type (bi-directional transistor, of column 3, line 53 of the aforesaid U.S. patent). A circuit arrangement having asymmetrical transistor has the disadvantage, however, that the duration of the switching pulses cutting off the transistor must be exactly equal to the flyback time of the sawtooth current since it is necessary to drive the transistor immediately back into saturation at the beginning of the stroke time.

However, to drive the transistor so that its cut-off time is exactly equal to the flyback time is much too critical for practical purposes, since the cut-off time is determined by the switching signal and depends upon the adjustment of the oscillator supplying the switching signal, whereas the flyback time depends upon the value L of the overall inductance in the output circuit of the transistor, and upon the value C of the stray capacitances and additional capacitances, if any, in this output circuit. It is difficult to choose for each case, especially in mass production, the conditions in the oscillator and in the said output circuit so that the aforementioned requirement of equality is fulfilled. Moreover, the equality originally adjusted accurately may be subsequently lost due to aging or other variation in the circuit parameters during the use of the circuit arrangement.

For all these reasons, a circuit arrangement having a symmetrical transistor the line output transistor is not suitable for practical use.

Another known deflection circuit uses an asymmetrical transistor in which the damper diode is dispensed with by forward biasing the base-collector junction of the transistor so that a reverse current can flow through the deflection coil via said base-collector junction at the start

of the stroke period. This circuit exhibits a discontinuity in the linear portion of the sawtooth current at the point the current path changes from base-collector to emitter-collector.

The circuit arrangement in accordance with the invention provides a solution which renders it suitable for practical use and it is characterized in that the transistor used is an essentially asymmetrical or unidirectional transistor. In addition, the duration of the pulses of the switching signal which cut-off the transistor is longer than the flyback time of the sawtooth current so that at the beginning of the stroke time, a current, reverse to that at the end of the stroke time, may flow through the deflection coils via the forward biased base-collector diode of the transistor, while the supply voltage of the transistor exceeds by many times, for example, by ten times, the peak-to-peak value of the switching signal applied between the base and the emitter electrode. The inductive coupling includes an inductance directly connected between the base and the emitter of the transistor.

A few possible embodiments of circuit arrangements in accordance with the invention will now be described more fully with reference to the accompanying figures, in which:

FIG. 1 shows the basic circuit arrangement in accordance with the invention,

FIGS. 2, 3 and 4 show equivalent circuit diagrams of the circuit arrangement shown in FIG. 1 for explaining its operation.

FIGS. 5a to 5g illustrate curves of currents and voltages that may occur in the circuit arrangement shown in FIG. 1,

FIG. 6 shows a second embodiment of a circuit arrangement in accordance with the invention in which the driver transistor is a symmetrical transistor,

FIGS. 7a to 7g show curves of currents and voltages that may occur in the circuit arrangement shown in FIG. 6,

FIG. 8 shows a third embodiment of the invention in which a capacitor is connected between the base electrode and the collector electrode of the output transistor in order to suppress parasitic oscillations,

FIG. 9 shows a further developed circuit diagram of the circuit arrangement of FIG. 8,

FIG. 10 shows a further embodiment of the invention.

In FIG. 1, the transistor T_1 is a driver transistor. The collector circuit includes a transformer 1. The primary winding 2 of the transformer 1 connects the collector electrode of the transistor T_1 to the supply voltage source $-V_s$. The switching signal 3, originating from an oscillator, not shown, is applied between the base electrode and the emitter electrode of the transistor T_1 . The switching signal releases the transistor T_1 during the flyback time of the sawtooth current that will flow through the deflection coils L_y and during part of the stroke time of the sawtooth current. The signal cuts off the transistor T_1 during the remaining part of the stroke time. The secondary winding 4 of the transformer 1 is connected between the base electrode B and the emitter electrode E of a line output transistor T_2 . The collector electrode C of the output transistor T_2 is connected to the parallel-combination of a deflection coil L_y and a capacitor C_y , while the emitter electrode E is connected to ground. Between the end of the said parallel-combination remote from the collector electrode and ground there is connected a supply voltage source which supplies a supply voltage V_H for the line output transistor T_2 . As will be described hereinafter, it is required for the circuit arrangement in accordance with the invention that the voltage V_H exceeds by many times the switching voltage across the base-emitter diode of the transistor T_2 . For example, in the embodiment shown in FIG. 1, the voltage V_H is equal

65
70

to 220 v., whereas the voltage V_s amounts to only 7 v. The transformation ratio of the transformer 1 is equal to 1:1. The voltage V_s and the transformation ratio determine the peak-to-peak value of the ultimate switching signal which is operative between base and emitter electrodes of the transistor T_2 via the secondary 4.

As stated in the preamble, the line output transistor T_2 of FIG. 1 is of a very particular structure. In the first place this transistor must be capable of withstanding a very high voltage.

Secondly, this transistor must essentially be asymmetrical, which implies that the transistor T_2 must be capable of withstanding a base current which, at the beginning of the stroke time, is equal to the current flowing through the collector circuit. Therefore, the base region of the transistor T_2 must be calculated for conveying such a high current. As will be explained hereinafter, finally a situation arises in which the base-collector diode D_{C2} and the base-emitter diode D_{E2} are unblocked simultaneously. As a matter of course, the transistor T_2 must be suitable for use in this situation in which the diodes are both unblocked and convey comparatively high currents. A possible method of constructing such a transistor has been described in a copending U.S. application, Ser. No. 587,456, filed Oct. 18, 1966.

In order to explain the foregoing and the operation of the circuit arrangement shown in FIG. 1, FIG. 2 shows the equivalent circuit diagram of the circuit arrangement of FIG. 1. In this figure, the transistor T_1 is represented as a switch T_1 . The transformer 1 is assumed to be an ideal transformer having an inductance value L_x and connected in parallel with the base-emitter diode D_{E2} . In view of the fact that the transistor T_2 is an npn-type transistor, the anode of this diode is connected to the base point B while its cathode is connected to the emitter point E, which points correspond with those indicated in FIG. 1.

The switch T_1 is connected in series with the supply voltage source V_s supplying the voltage applied between the base electrode B and the emitter electrode E of the transistor T_2 when the transistor T_1 is in the conductive state, which corresponds with the closed state of the switch T_1 in FIG. 2.

In FIG. 2, the diode D_{C2} represents the base-collector diode of the transistor T_2 . This diode is shunted by a source 5 which supplies the amplified emitter current αI_E . The equivalent circuit diagram of FIG. 2 also includes the horizontal deflection coil L_y , its bridging capacitance C_y and the supply voltage source V_H . As is apparent from FIG. 2, a current source αI_C is not included. In fact, this source would have to be connected in parallel with the base-emitter diode D_{E2} , but, as stated above, the transistor T_2 is essentially asymmetrical, which means that the current source αI_C supplies a negligibly low current and may therefore be omitted.

The switching signal 3 ensures that the transistor T_1 operating as a driver transistor is alternately in the conductive and in the non-conductive state. Consequently, a pulsatory signal of a value $(1+b)V_s$ at the instant t_2 and of a value $(1+c)V_s$ at the instant t_4 is produced across the secondary 4. This can be explained as follows. If the transistor T_1 is conducting (switch T_1 is closed), the primary 2 is at a voltage of V_s volt. Since the transformation ratio between the windings 2 and 4 is approximately 1:1, the value of the voltage at the secondary 4 is equal to that of the voltage at the primary 2. Consequently, in the time interval from 0 to t_2 in which the transistor T_1 is conducting, the voltage at the secondary 4 is also equal to V_s volt. However, since the D.C. component is lost due to the inductive coupling between the windings 2 and 4, the switching signal V_{BE2} operative between the base electrode and the emitter electrode of the transistor T_2 will have an average value of 0, which is represented by the line 6 in FIG. 5a. Since the area below the line 6

must consequently be equal to that above it, the voltage exceeds the line 6 by a value bV_s at the instant t_2 and by a value cV_s at the instant t_4 . As is apparent from FIG. 5a, the switching voltage V_{BE2} is not constant during the time the transistor T_2 conveys current, but slightly increases. This is due to the fact that during this period the emitter current I_{E2} is not constant but increases linearly, as is apparent from FIG. 5e.

Therefore, the voltage V_{BE2} has a negative value of V_s volt during the time interval from 0 to t_2 . However, at the instant t_2 the voltage V_{BE2} jumps from the value $-V_s$ to a value $+bV_s$. Hence, in FIG. 2, and also in the following FIGURES 3 and 4, the voltage source connected with the time switch T_1 supplies a direct voltage of V_s volt, i.e. the cut-off voltage operative between the base electrode and the emitter electrode of the transistor T_2 if the switch T_1 is closed during the time interval from 0 to t_2 . At the instant t_2 , the switch T_1 is opened and at that instant the voltage at the base electrode B is equal to $+bV_s$ volt. The starting point lies at the instant 0 and it is assumed that at this instant a current I_{Ly} flows through the deflection coil L_y , which current has the value indicated in FIG. 5b. At the instant 0, the switch T_1 is closed, which means that the transistor T_2 is cut off. The electromagnetic energy accumulated in the coil L_y as, a result of the current flowing through this coil at the instant 0, starts oscillating decrementally along a sinusoidal curve so that the frequency and the flyback time are determined by the values of L_y and C_y . This decremental oscillation occurs from the instant 0 to the instant t_1 , i.e. the flyback time of the sawtooth current I_{Ly} . The fact that this decremental oscillation actually dies out at the instant t_1 can be explained as follows. As a result of the sinusoidal decremental oscillation of the current I_{Ly} , the voltage across the parallel circuit oscillates decrementally along a sinusoidal curve. Consequently, the voltage V_{CE2} at the collector C of the transistor T_2 follows a curve as shown in FIG. 5f during the time interval from 0 to t_1 . This decremental oscillation of the voltage continues until the collector electrode C of the transistor T_2 becomes negative with respect to the base electrode B thereof. This is the case at the instant t_1 . If the collector electrode C is negative with respect to the base electrode B, the base-collector diode D_{C2} conveys a current I_{C2} , so that the situation arises which is shown in FIG. 3. If the switch T_1 is closed, the diode D_{E2} does not convey current so that the current $\alpha I_{E2}=0$. Therefore, the current source 5 and the base-emitter diode D_{E2} are omitted in FIG. 3. However, if the diode D_{C2} is conducting, a constant voltage constituting the sum of the voltages V_H and V_s is again produced across the deflection coil L_y . The sum of these voltages therefore determines the slope of the sawtooth current which flows from the instant t_1 to the instant t_2 . Moreover, the decremental oscillation of the circuit $L_y C_y$ is finished at the instant t_1 . When the transistor T_2 has the aforementioned properties, it is achieved that the collector current I_{C2} flowing during the time interval from t_1 to t_2 is equal to the instantaneous base current I_{B2} , since the emitter current I_{E2} and the amplified emitter current αI_{E2} are both equal to 0. Therefore, the base current I_{B2} will have the same configuration as the collector current I_{C2} during the time interval from t_1 to t_2 , which is clearly apparent from FIGS. 5c and 5d. In FIG. 5c, the collector current I_{C2} flowing during the time interval from t_1 to t_2 is negative, since it is opposite to the current αI_{E2} which is the normal collector current when the transistor T_2 actually operates as a transistor. The current $I_{C2}=I_{B2}$ flows back through the switch T_1 . During the flyback time from 0 to t_1 , when I_{B2} is not yet present, the current through the switch T_1 is determined by

$$I_x = \frac{V_s}{L_x} t_1$$

that is to say by the value of the coil L_x and the applied voltage V_s . During the time interval from t_1 to t_2 , the current through the switch T_1 is equal to $I_x - I_{BE2}$.

This is apparent from FIG. 5g in which the collector current I_{C1} is shown. Therefore, the current flowing back through the base circuit of the transistor T_2 reduces the current of the driver transistor T_1 . The interrupted line in FIG. 5g indicates the path of the current flowing through T_1 if this effect did not occur.

This effect can be considered as an additional advantage of the circuit arrangement in accordance with the invention, since, as is apparent from the numbers stated in FIG. 5c, the collector current I_{C2} has a value of $-0.6A$ at the instant t_1 , which value decreases to approximately $0.3A$ at the instant t_2 . In this time interval the base current I_{B2} is equal to the collector current I_{C2} . Since the base current also has a comparatively high value owing to the low value of α' during the remaining part of the time interval, i.e. from t_2 to t_4 , this means that the base current I_{B2} constantly has a comparatively high value. This current must ultimately be supplied through the driver transistor T_1 . If the advantage of the decrease in the collector current I_{C1} during the time interval t_1 to t_2 would not be found, the full magnetization current for the transformer 1 would have to be supplied by the transistor T_1 in order to provide the possibility of the desired base current I_{B2} flowing during the time interval from t_2 to t_4 . During the time interval from t_1 to t_2 , the collector current I_{C1} would then have a configuration as represented by the interrupted line of FIG. 5g. In consequence thereof, the average collector current I_{C1gem} would not have the value shown by the dot-and-dash line 7 in FIG. 5g but this value would be considerably higher. This would imply not only that the driving power supplied is much higher but also that the transistor T_1 must be capable of withstanding a much greater dissipation. This is avoided by the favourable additional effect of the decreasing collector current I_{C1} during the time interval t_1 to t_2 .

At the instant t_2 , the switch T_1 is opened and a situation arises as shown in the equivalent diagram of FIG. 4. As appears from FIG. 5a, when the switch T_1 is opened, the voltage at the base electrode jumps to a value $+bV_s$. This implies that, when the switch T_1 is opened, the voltage at point B jumps by $(1+b)V_s$ volt. As is apparent from FIG. 5f, however, the voltage at the point C will also jump by the same value, since the base-collector diode D_{C2} continues to conduct. For the voltage at the anode of diode D_{C2} becomes positive so that the diode tends to remain conducting. The voltage across a conducting diode is substantially zero, however, so that a jump of the voltage at the point B results in a jump of the voltage at the point C. Owing to the said voltage jump, the voltage across the coil L_y is also varied. When the switch T_1 was closed the voltage across this coil was equal to $V_H + V_s$ volt, and after the instant t_2 this voltage is equal to $V_H - bV_s$ volt. Since the voltage V_H is very high, however (in the relevant embodiment 220 v.), and the voltage V_s is relatively low, in this case 7 v., the voltage $(1+b)V_s$ volt, which is the difference between the voltages across the coil L_y before and after the instant t_2 , is negligibly low with respect to the voltage V_H . The bend occurring in the collector current I_{C2} and hence in the current I_{Ly} as a result of this voltage jump is therefore also negligibly small.

This bend could therefore not be observed on an oscillograph.

Consequently, although the collector current I_{C2} substantially does not vary when the switch T_1 is opened, the base current I_{B2} and the emitter current I_{E2} of the transistor T_2 and the collector current I_{C1} of the transistor T_1 are varied indeed, since when the switch T_1 is opened, the transistor current I_{C1} becomes 0.

Since the current I_x through the coil L_x cannot jump

either and this current was equal to $I_{B2} + I_{C1}$ before the instant t_2 , after the instant t_2 the base current I_{B2} must be equal to I_x due to the disappearance of the collector current I_{C1} . However, since the current I_x cannot jump, this jump must be effected by the base current I_{B2} . As is apparent from FIG. 5d, the base current I_{B2} jumps by slightly more than $0.6A$ (from approximately $0.3A$ to slightly more than $0.9A$), which is just the value of the collector current I_{C1} at the instant t_2 . Since the collector current I_{C2} substantially does not vary, this additional current must be passed by the base-emitter diode D_{E2} through which an emitter current I_{E2} begins to flow which exhibits a jump equal to that of the current I_{B2} .

Since, as stated above, the diode D_{C2} remains unblocked at the instant t_2 and the collector current I_{C2} is not varied, the existing situation remains actually unchanged and the diode D_{C2} may act as a shortcircuit for the source 5 so that the current αI_{E2} does not yet flow in spite of the fact that the emitter current I_{E2} is no longer 0.

This situation is maintained approximately to the instant t_3 at which time the collector current I_{C2} becomes 0. This means that at this instant the electromagnetic energy has completely disappeared from the deflection coil L_y . Owing to the fact that by opening the switch T_1 at the instant t_2 all the conditions for a normal operation of the transistor T_2 have already been fulfilled, the base current applied from the instant t_3 keeps the transistor T_2 in the saturated state.

In the embodiment shown in FIG. 1, α' has a low value so that also in normal operation the current amplification from the base to the collector is small in the time interval from t_3 to t_4 . With currents as shown in FIG. 5, α' amounted to 1.5. Otherwise, the operation of the line output transistor T_2 in the time interval from t_3 to t_4 is similar to that of a conventional transistor. As a result, the current I_{C2} , and hence the current through the deflection coil L_y , will increase to a given value which, as stated above, is determined by the voltage $V_H - bV_s$. At the instant t_4 , the switch T_1 is closed again and the cycle described before is repeated.

Although in the foregoing it is assumed that the transistor T_2 is an npn-type transistor and that the transistor T_1 is a pnp-type transistor, these transistors may be of any other type. Only the polarity of the applied supply voltages V_H and V_s and the direction of winding of the transformer 1 must be taken into account.

Alternatively, the collector C of the transistor T_2 may be grounded instead of the emitter E. In this case, it is desirable also to exchange the parallel-combination of L_y and C_y with the supply voltage source V_H so that in fact a grounded collector arrangement is obtained. The operation is analogous, however, to that of the arrangement of FIG. 1.

It is not always necessary to establish the coupling with the base electrode of the transistor T_2 via a transformer. One coil could be sufficient which is connected in parallel between the base electrode and the emitter electrode of the transistor T_2 . In this case, the switching transistor T_1 may be arranged between the supply voltage source V_s and the coil.

A second embodiment of a circuit arrangement in accordance with the invention is shown in FIG. 6. This embodiment differs from that of FIG. 1 in that instead of an asymmetrical driver transistor T_1 a symmetrical transistor of the npn-type is used. As a result, the switching signal must also be of opposite polarity and therefore has a configuration as represented by the signal 3' in FIG. 6. Furthermore, the driver transistor T_1 is now energized by means of an RC circuit consisting of the resistor 8 and a large capacitor 9. Moreover, the transformer 1 is chosen to be considerably larger than the corresponding transformer 1 of FIG. 1. Consequently, the magnetization current required to maintain the desired base current I_{B2} during the time interval from t_2 to t_4 may be considerably

lower than in the corresponding case of FIG. 1, because the current

$$I_x = \frac{V_s}{L_x} t$$

as shown in FIG. 3, flows through the coil L_x and will be considerably lower in the circuit arrangement of FIG. 6 than in that of FIG. 1 during the interval from 0 to t_1 . (cf. FIGS. 5g and 7g).

Owing to the fact that during the time interval from 0 to t_1 the current I_{C1} has assumed a much lower value due to the increase of L_x resulting from the increase of the transformer 1, whereas the collector current I_{C2} which begins to flow at the instant t_1 has not varied at all, the decrease of the collector current I_{C1} will be such that this collector current changes its sign, which is clearly apparent from FIG. 7g. For this reason, the transistor T_1 of FIG. 6 is a symmetrical transistor. Of course, start could in principle be made again from the fact that the inversion of the collector current I_{C1} would result in that the base-collector diode of the transistor T_1 would be unblocked. This would mean, however, that an additional current would be derived from the oscillator supplying the switching signal 3'. This would have an unfavourable reaction on the oscillator so that its frequency could vary and consequently the synchronization of the horizontal deflection could be lost. However, when a symmetrical transistor is used and when it is ensured that the transistor T_1 is constantly kept in the saturated state by the base current I_{B1} , this risk can be avoided. This also influences the release of the transistor T_1 , for in the time interval from t_1 to t_5 the driver current is negative. This means that the collector electrode of the transistor T_1 acts as an emitter. Consequently, the base-collector diode of the transistor T_1 in fact would have to be cut off by the switching-off voltage, which is virtually impossible due to the current superimposed from the collector circuit. Preferably the instant of switching off the transistor T_1 is therefore shifted from t_2 to t_5 . This means that the time interval from 0 to t_2 as shown in FIG. 7, which holds for the circuit arrangement of FIG. 6, is lengthened with respect to that shown in FIG. 5 which holds for the circuit arrangement of FIG. 1. However, it should be taken into consideration that the instant t_2 must absolutely precede the instant t_3 , since from the instant t_3 the transistor T_2 must be able to operate again as a normal transistor, which is possible only in case the transistor T_1 is cut off. As is apparent, however, from FIG. 7, there is still a wide choice since the time interval from t_5 to t_3 constitutes a fairly great fraction of the cycle T.

As appears from FIGS. 7c and 7d, the α' for the transistor T_2 of FIG. 6 is chosen considerably higher than in the embodiment shown in FIG. 1. In the case of FIG. 6, the α' is chosen to be equal to 6. It will be appreciated, however, that both in the case of FIG. 1 and in that of FIG. 6 other values may also be chosen for α' . When a symmetrical driver transistor T_1 is used, the α' of the transistor T_2 may consequently assume considerably higher values. Thus, a value of $\alpha'=10$ or even higher is still possible.

In the foregoing, it has always been assumed that $V_H=220$ v., while $(1+b)V_s \approx 7$ v. This results in a ratio of

$$\frac{220}{7} \approx 30$$

which means that the supply voltage applied to the transistor T_2 is approximately 30 times the peak-to-peak value of the switching signal applied between the base electrode and the emitter electrode of the transistor T_2 . In general, a satisfactory circuit operation is obtained if the ratio

$$\frac{V_H}{(1+b)V_s} \geq 10$$

holds for transistor T_2 . However, it will be appreciated that said ratio cannot be reduced without limitation, since otherwise the bend in the sawtooth current I_{Ly} occurring at the instant t_2 becomes excessively great. Moreover, at too low a value of V_H , the collector current I_{C2} would have to assume too high a value, since the product of current and voltage determines the power required to obtain in a given coil L_y the desired deflection of the electron beam. Thus, if V_H is chosen lower, I_{C2} must be chosen higher. In the time interval from t_1 to t_2 it holds that $I_{C2}=I_{B2}$ so that a higher I_{C2} results in a higher I_{B2} , which might cause the base current to assume an excessively high value. It may therefore be said that a ratio between V_H and V_s of 10:1 substantially is the minimum ratio at which the circuit arrangement can operate satisfactorily.

As already stated above, in the circuit arrangement of FIG. 6, the peak-to-peak value of the switching signal 3' must have a value such that the driver transistor T_1 remains in the saturated state during the time interval from t_1 to t_2 so that it is ensured that the switching signal 3' switches the transistor T_1 , and that the voltages applied to the collector electrode cannot cause this transistor to be cut off prematurely.

It is further apparent from FIG. 7g that the average collector current of the transistor T_1 is very low due to the fact that this current becomes negative during the time interval from t_1 to t_5 . This average current could even be reduced to 0 if it holds that $O_1+O_3=O_2$, O_1 , O_2 and O_3 denoting the areas shown in FIG. 7. However, in practice O_1+O_3 is preferably chosen to be greater than O_2 so that a positive current flows through the resistor 8. However, this current may be kept very low by choosing O_2 to be only slightly different from O_1+O_3 . In this case, the dissipation in the resistor 8 is comparatively low in spite of the fact that a high resistance value is required for this resistor. The correct value of the voltage V_s produced across the capacitor 9 depends upon the ratio between the areas O_1 , O_2 and O_3 which, with a given design of the output transistor T_2 , in turn depends upon the inductance value of the coil L_x and upon the value of the resistor 8 at a given supply voltage V_H .

The circuit arrangement shown in FIG. 6 therefore affords the advantage, in comparison with that of FIG. 1, that a separate low supply voltage V_s need not be available. Thus, it becomes attractive to derive from this circuit arrangement the supply voltages for the remaining parts of a transistorized television receiver. For in this case, a supply transformer is economized. This may be achieved, for example, by coupling the deflection coils L_y with a line output transformer and by providing the transformer with a tapping from which pulses of low amplitude can be derived. After being rectified and smoothed, these pulses can produce the supply voltage for the remaining transistors in the receiver. It must be taken into account that in this case the oscillator supplying the switching signal 3' is also supplied with this supply voltage. However, this supply voltage is not present before the transistor T_1 and T_2 are driven. Therefore, in order to render the circuit arrangement self-starting, it must be ensured that this drive is brought about automatically when the supply voltage V_H is switched on. This may be achieved, for example, by providing a feedback capacitor between the base and collector electrode of transistor T_1 so that this transistor becomes self-oscillating when the supply voltage V_H is switched on. However, if the value of the feedback capacitor is correctly chosen, then when the switching signal 3' becomes available it has a greater influence than the feedback action so that the transistor T_1 again becomes a normally driven driver transistor.

It follows from FIGS. 5b and 7b that the current flowing through the coil L_y before the instant t_1 flows back through the capacitor C_y . After the instant t_1 , this capacitor current must be taken over by the collector cir-

cuit of transistor T_2 . This means that the collector current thereof must jump from zero to the value that the capacitor current has at the instant t_1 . This is possible owing to the fact that, as stated above, the base collector diode D_{C2} is released at the instant t_1 . As shown in FIG. 8, however, the connections with the coil L_y include stray inductances L_p . If, due to the inductance L_p , the current should be 0 before the instant t_1 , while after this instant a current would abruptly begin to flow through this inductance, the inductances L_p are abruptly excited, which together with stray capacitances in the circuit gives rise to stray oscillations at the beginning of the stroke time. This is the case if the capacitor C_y is connected in parallel with the coil L_y .

In order to prevent the occurrence of these stray oscillations, a further improvement of the circuit arrangement in accordance with the invention consists in that the capacitor C_y is connected between the base electrode B and the collector electrode C of the transistor T_2 . From the instant t_1 the capacitor current is then simply passed on to the diode D_{C2} which opens at this instant. This does not involve a change of the current path. An abrupt excitation of the stray inductances L_p and hence the appearance of stray oscillations are avoided.

Finally, FIG. 9 shows in greater detail a circuit diagram of the circuit arrangement of FIG. 8. It appears from FIG. 9 that the supply voltage V_H is obtained by a direct rectification of the AC supply voltage. For this purpose, the supply voltage is applied through the switch S to a rectifier D_1 which rectifies the supply voltage and which, after smoothing of this voltage by the elements R_3 , C_3 and C_4 , produces across the capacitor C_3 the DC supply voltage V_H . The supply voltage V_H is applied to the line output transformer 10 between its windings 11 and 12 . These windings are split up in order to ensure that the voltage pulses 14 and 15 produced at the ends of the windings 11 and 12 , respectively, have opposite polarities. It is favourable that the deflection coil L_y be connected in series with the linearity control member L_2 and the blocking capacitor C_2 between the ends of the windings 11 and 12 , since in this case stray inductances in the windings 11 and 12 cannot give rise to undesired interferences. As a result of the opposite polarities of the pulses 14 and 15 , the long conductors extending from the ends of the windings 11 and 12 to the deflection coil L_y slipped around the neck of the display tube will not emit radiation.

The transformer 10 further includes a high-voltage winding 16 which steps up the pulses so that, after being rectified in the high-voltage diode D_2 , they supply the acceleration voltage for the final anode of the display tube. The acceleration voltage is fed to this final anode through the conductor 17 .

Finally, it should be noted that if the α' of the output transistor T_2 should not be chosen excessively high and if nevertheless the driver transistor T_1 should not be supplied from a separate supply source, the circuit arrangement shown in FIG. 10 may be used. This circuit arrangement is a further development of that shown in FIG. 6. The capacitor C_4 is arranged in the manner shown in FIG. 8 and the deflection coil L_y is connected in series with capacitor C_2 in the manner shown in FIG. 9. The circuit has an output transformer 10 , an additional diode 19 connected to the secondary 20 of the transformer 10 , and a resistor 21 .

If $1\frac{1}{2}\alpha' 10$ ($\alpha'=1\frac{1}{2}$ example of FIG. 5, $\alpha'=10$ example of FIG. 7), the value of the base current I_{B2} in the time interval t_2 to t_4 lies between the values indicated in FIGS. 5d and 7d. A higher base current in this time interval implies that in the time interval $0 \rightarrow t_2$ a greater amount of electromagnetic energy would have to be introduced into the inductor L_x of the driver transformer 1 . The driver current I_{C1} and consequently also its average value must therefore increase. The value of the current I_{C1} will also lie between the values indicated in FIGS. 5g and 7g.

A higher average driver current I_{C1gem} results in a higher dissipation even if the resistor 8 is reduced. ($V_{R8}=I_{C1gem} \cdot R_8$, dissipation $E_{R8}=I_{C1}^2 gem R_8$). Therefore, if a low-voltage transistor were used for the driver transistor T_1 , the losses in resistor 8 would become excessively high.

The solution of this problem is illustrated in FIG. 10. Resistor 21 has a double function. When the circuit arrangement starts after switching on the supply voltage V_H , the resistor 21 acts together with resistor 8 as a voltage divider the required supply voltage is supplied from the junction of resistors 8 and 21 to the transistor T_1 . Resistors 8 and 21 may both be high since the starting current is fairly low. This current need be only so high that the pulses V_{CE2} (cf. FIGS. 5f and 7f) produced during the fly-back time $0 \rightarrow t_1$ and induced in the secondary 20 have an amplitude exceeding the voltage at the junction of the resistors 8 and 21 . The diode 19 then becomes conducting at the peaks of these pulses and consequently rectifies these pulses. The rectified voltage is smoothed by the network $9-21$ so that an additional amount of energy is supplied to the supply circuit for the driver transistor T_1 .

Thus, this circuit arrangement is automatically matched to the α' of the output transistor T_2 . Therefore, if α' originally had a high value, I_{C1gem} is low. The voltage drop across resistor 8 is low and the diode 19 remains blocked during the circuit operation. If α' decreases due to ageing, I_{C1gem} and consequently the voltage drop across resistor 8 increases so that the diode 19 becomes operative. A satisfactory operation of the circuit arrangement without unnecessary dissipation in resistor 8 is thus ensured in all circumstances.

Moreover, wider tolerances of α' of transistor T_2 are now permissible. If α' is high, the diode 19 does not become operative, whereas if α' is low, the diode becomes operative.

What is claimed is:

1. A deflection circuit for producing a sawtooth current having a given flyback period in the line deflection coils of a display tube comprising, a unidirectional transistor having an output circuit to which the deflection coils are connected, inductive coupling means including an inductor directly connected between the base electrode and the emitter electrode of said transistor, means for applying to said inductive coupling means a pulsatory switching signal having a peak-to-peak amplitude which periodically switches the transistor between a cut-off condition and a saturation condition, the duration of the portion of the switching signal pulse which cuts off the transistor being longer than the flyback period of the sawtooth current so that at the beginning of the forward stroke a voltage is developed across said deflection coils of an amplitude and polarity to cause a reverse current to flow through the deflection coils via the base-collector diode junction of the transistor, and a supply voltage coupled to the transistor that exceeds by at least 10 times the peak-to-peak value of said switching signal applied between the transistor base and emitter electrodes.

2. A circuit as claimed in claim 1 wherein the inductive coupling means comprises a transformer having a primary winding and a secondary winding, means directly connecting the two ends of the secondary winding to the base electrode and the emitter electrode of the transistor, a driver transistor, a second source of supply voltage, means connecting the primary winding in series with the emitter-collector path of said driver transistor to said second supply voltage, the amplitude of said second supply voltage being at least 10 times lower than that of the supply voltage of said unidirectional transistor.

3. A circuit arrangement as claimed in claim 2 wherein the transformation ratio between the primary and the secondary windings of the transformer is 1:1.

4. A circuit arrangement as claimed in claim 2 wherein the inductance value of said inductive coupling means

is chosen to be so high that the current flowing through it during the flyback period of the sawtooth current is lower than the inverse collector current that flows in said unidirectional transistor immediately at the beginning of the stroke period via its base-collector diode junction, whereby the direction of the emitter-collector current of the driver transistor reverses at the beginning of the forward stroke.

5. A circuit arrangement as claimed in claim 4 wherein the driver transistor is a symmetrical transistor.

6. A circuit arrangement as claimed in claim 5 wherein said second voltage supply source for the driver transistor comprises, a capacitor, a resistor, and means connecting the capacitor to the voltage supply source of the unidirectional transistor by means of said resistor.

7. A circuit arrangement as claimed in claim 6 wherein the inductance value of the inductive coupling means is chosen so that said driver transistor draws an average current differing from zero from the supply voltage source of the unidirectional transistor.

8. A circuit arrangement as claimed in claim 1 further comprising a capacitor that resonates with the deflection coils to determine the flyback period of said sawtooth current, and means connecting said capacitor between the base electrode and the collector electrode of the unidirectional transistor.

9. A deflection circuit for producing a sawtooth current having a given flyback period in a deflection coil comprising, a unidirectional semiconductor device having emitter, base and collector electrodes, means for coupling said deflection coil to the output circuit of the semiconductor device, inductive coupling means comprising an inductor directly connected between the base and emitter of said semiconductor device, means for applying to said inductive coupling means a control voltage wave 30 having a peak-to-peak amplitude and polarity to periodically cut off current flow in said semiconductor device,

the duration of the cut-off period of said voltage wave being longer than said given flyback period so that a voltage reversal occurs across said deflection coil of a magnitude and polarity to forward bias the base-collector junction of said semiconductor device during a portion of the period when said voltage wave cuts off the semiconductor device, and a source of direct voltage coupled to said collector electrode of a magnitude at least ten times the peak-to-peak voltage of said control voltage.

10. A circuit as described in claim 9 further comprising means connecting said deflection coil and said direct voltage source in series across the emitter-collector path of said semiconductor device.

11. A circuit as described in claim 9 wherein said semiconductor device is connected in the common emitter configuration, said circuit further comprising a capacitor connected between the base and collector of said semiconductor device so as to resonate with the deflection coil during the flyback period of the sawtooth current.

12. A circuit as described in claim 11 further comprising a drive transistor having an output electrode coupled to said inductive coupling means and to a source of direct supply voltage, a deflection transformer having a primary winding coupled to the collector electrode of said semiconductor device and a secondary winding, a diode connected between said secondary winding and said source of direct supply voltage for coupling a portion of the flyback pulses to said supply voltage source.
